[57] ABSTRACT

An improved device and method is provided for periodically, singly dispensing a plurality of stacked aligned receptacles and advancing the dispensed receptacles to a filling station. Receptacle contact members are provided for contacting the first, bottommost receptacle of the stacked array of receptacles, lowering the bottommost receptacle and the upstanding stack located thereabove until the first, bottommost receptacle approaches contact with a support or transport bed. The stack is permitted to fall when the first, bottommost receptacle is somewhat above the support bed, falling out of reach of the receptacle contact member. The receptacle contact member then contacts the second receptacle from the bottom and raises it and the stacked receptacles thereabove off of the bottommost first receptacle which is then periodically advanced by a transport bed toward the filling station along the receptacle support bed. The support bed includes guides for maintaining a received receptacle in contact therewith as said receptacle is advanced therewith toward the filling station.

RECEPTACLE UNSTACKING AND TRANSPORTING DEVICE

The present invention relates generally to dispensing and delivery machines, and in particular, to a machine for supplying a plurality of receptacles, one at a time, from a supply stack to a filling station.

Various machines have been available for use by manufacturers and suppliers of packaged materials for automatically dispensing and filling receptacles with various products. Machines have even been devised to singly supply a succession of receptacles for receipt of an item therein, supplied one at a time. Such a device is shown and described in U.S. Pat. No. 2,613,861 which issued Oct. 14, 1952.

The device shown in the '861 patent feeds a plurality of stacked receptacles to a rod-dispensing mechanism which provides rods one at a time to rod-receiving cavities therein. The receptacles are supplied by a supply mechanism which urges the bottommost receptacle of a stack of receptacles out from under the stack with the entire weight of the stack bearing down on the bottommost stack. A succession of receptacles is advanced toward the rod-dispensing mechanism in succession for continuous delivery of rods thereto. No mechanism is provided for relieving the force of the weight of the stacked array of receptacles from the receptacle to be dispensed. Further, no means is provided for preventing one receptacle from overriding and buckling with respect to an adjacent receptacle in traveling from the receptacle supply to the delivery station wherein the receptacles are filled.

Of recent times it has been necessary to automatically supply a plurality of receptacles for delivery of devices thereto wherein the receptacles are of a fragile nature that will not admit of dispensing from a stacked array while bearing the weight of the entire stack on the receptacle to be dispensed.

For example, it is often necessary to provide a positive indication of when syringes have been removed from a multiple-syringe receptacle. This is necessary as the syringes may contain valuable medications therein or narcotics which require strict control. To ensure that there is no misuse or theft thereof, receptacles have been devised which are manufactured of relatively light semi-rigid plastic. The receptacles contain various compartments which must be made strong enough to separately contain the syringes within the receptacles and light and fragile enough to permit easy breakage of individual compartments when it is desired to remove a single syringe therefrom thereby providing easily visible evidence of removal.

The required fragility of the receptacle prevents the stacking of a supply of receptacles for automatic dispensing thereof by, for example, the device of the '861 patent. Accurate reliable delivery of the bottommost of said receptacles, with the weight of an entire stack thereon, would require sufficient force to fracture the bottommost receptacle.

In addition, the lightness required by the fragility requirement of the above-noted receptacles tends to promote buckling of adjacent advancing receptacles with respect to one another. Buckling of adjacent receptacles causes the advancing and supply machinery to become jammed and inoperative.

Consequently, while the prior art receptacle-advancing and supply mechanisms have value with receptacles

which are strong enough to permit advancing despite the weight thereon of a stacked array, and which are heavy enough to permit advancing to a filling station without danger of adjacent receptacles buckling with respect to one another, they are of little if any use when it is desired to automatically deliver and supply lightweight receptacles in a reliable manner.

It is an object of the present invention to provide a device for singly delivering a plurality of lightweight receptacles and supplying thereof to a filling station in substantially undamaged condition without interrupting continuous operation of the device.

It is a more particular object of the present invention to provide a mechanism for singly dispensing one of a plurality of stacked receptacles by removing the weight of the stacked array from a delivered receptacle and advancing the delivered receptacle longitudinally along a delivery path to a filling station for receipt of a plurality of items therein while preventing movement of advancing receptacles relative to one another except in the direction of their advance along the delivery path without being removed from the delivery path transversely with respect thereto.

Broadly, the apparatus of the present invention can be used for dispensing a receptacle and delivering the receptacle to a station for receipt of an item therein. The improvement of the present invention comprises generally upstanding channel means for maintaining a plurality of receptacles in aligned stacked array, a support bed and receptacle dispensing means for periodically dispensing the lowermost of said stacked receptacles onto the support bed. First drive means are provided for operating the receptacle dispensing means. Receptacle advancing means are provided for periodically advancing the dispensed receptacle toward the station along the support bed. Second drive means are provided for operating the receptacle advancing means. The receptacle dispensing means includes means for normally supporting the stacked array of receptacles by contacting the lowermost of the stacked array of receptacles. Means are provided for periodically lowering the stack of receptacles toward said support bed until the lowermost of the stacked receptacles contacts the support bed. The receptacle dispensing means includes means constructed and arranged for contacting the next to lowermost of the stacked receptacles when the lowermost receptacle is in contact with the support bed and raising the next to lowermost receptacle and the stack, the lowermost receptacle thereby remaining in contact with the support bed. The station is located in operative relation to the support bed and is spaced from the dispensing means a given distance along said support bed. The support bed includes means for guiding the advancing receptacle and is constructed and arranged to maintain the advancing receptacle in contact with the support bed.

The method of the present invention includes periodically singly supplying one of a plurality of stacked receptacles for delivery to a filling station comprising stacking a plurality of receptacles in generally upstanding vertically movable array. Supporting the lowermost of the stacked array of receptacles above a support bed. Periodically lowering the lowermost and the stacked array of receptacles until the lowermost receptacle contacts the transport bed. Raising the next to lowermost receptacle and the stacked array of receptacles supported thereabove off of and out of contact with said lowermost receptacle. Advancing the lower-

most receptacle along the support bed while maintaining the next to lowermost and said stacked array of receptacles out of contact with said lowermost receptacle. Lowering the previously next to lowermost receptacle and the stacked array of receptacles located thereabove until the previously next to lowermost receptacle contacts the transport bed. Raising the receptacle above the previously next to lowermost receptacle and the stacked array of receptacles located thereabove off of and out of contact with the previously next to lowermost receptacle. Advancing the previously next to lowermost receptacle into abutting relation with the previously lowermost receptacle along the support bed toward the filling station including maintaining the previously lowermost and the previously next to lowermost receptacles in substantially abutting contact with each other and with the support bed during the advancing step.

The above brief description as well as further objects, features and advantages of the present invention will be more fully understood by reference to the following detailed description of the presently preferred but nonetheless illustrative embodiment in accordance with the present invention, when taken in conjunction with the accompanying drawing, wherein:

FIG. 1 is a top plan view of the dispensing and delivery device of the present invention;

FIG. 2 is a side elevational view of the apparatus of FIG. 1 with parts thereof shown in section;

FIG. 3 is a front elevational view of a machine embodying features of the present invention;

FIG. 4 is a side elevational view taken from the left of FIG. 3 showing the machine of FIG. 3 with parts thereof broken away;

FIG. 5 is a fragmentary side elevational view similar to FIG. 4 showing an alternate embodiment of a feature of the present invention;

FIG. 6 is a rear elevational view of the machine of FIG. 3 with parts thereof broken away;

FIG. 7 is a top plan view of the machine of FIG. 3, with parts thereof broken away;

FIG. 8 is a top plan view of the machine of FIG. 3, with parts thereof broken away, taken substantially along the line 8—8 of FIG. 3 and looking in the direction of the arrows;

FIG. 9 is a top plan view of the receptacle-dispensing apparatus of the present invention on an enlarged scale and taken substantially along the line 9—9 of FIG. 6 and looking in the direction of the arrows.

FIG. 10 is a rear elevational section view showing the receptacle-dispensing apparatus arranged with a stack of receptacles with the lowermost receptacle resting on a support bed taken substantially along the line 10—10 of FIG. 3 and looking in the direction of the arrows;

FIG. 11 is a rear elevational section view of the apparatus of FIG. 10 with the receptacle-dispensing apparatus shown lifting the stacked array of receptacles by contacting the next-to-lowermost receptacle with the lowermost receptacle remaining on the support bed;

FIG. 12 is a fragmentary side elevational view of a device embodying objects and features of the present invention on an enlarged scale;

FIG. 13 is a perspective view of part of the receptacle-advancing and guiding apparatus of the present invention used for advancing a receptacle; and,

FIG. 14 is a perspective view of part of the receptacle-advancing and guiding apparatus of the present invention for advancing a long receptacle.

FIG. 15 is a fragmentary front view of the syringe delivery apparatus of the machine of FIG. 3 prior to dispensing of a plurality of syringes into a receptacle disposed thereunder;

FIG. 16 is an enlarged fragmentary front elevational view of the apparatus of FIG. 15 with syringes shown delivered to the receptacle disposed thereunder;

FIG. 17 is a fragmentary sectional view taken substantially along the line 17—17 of FIG. 4 and looking in the direction of the arrows;

FIG. 18 is a detailed front view of the apparatus of FIG. 16;

FIG. 19 is a sectional view of a brake apparatus taken substantially along the line 19—19 of FIG. 18 and looking in the direction of the arrows;

FIG. 20 is a sectional view taken substantially along the line 20—20 of FIG. 7 and looking in the direction of the arrows;

FIG. 21 is a perspective view of the syringe delivery apparatus of FIG. 3;

FIG. 22 is a sectional view of the syringe delivery apparatus of FIG. 21 taken substantially along the line 22—22 of FIG. 21 and looking in the direction of the arrows;

FIG. 23 is a top plan view of a syringe guide for use with the machine of FIG. 3;

FIG. 24 is a sectional view of the syringe guide of FIG. 23 taken substantially along the line 24—24 of FIG. 23 and looking in the direction of the arrows;

FIG. 25 is a sectional view of an alternate syringe guide similar to the syringe guide of FIG. 24;

FIG. 26 is a sectional view of the syringe guide of FIG. 23 taken substantially along the line 26—26 of FIG. 23 and looking in the direction of the arrows;

FIG. 27 is a top plan view of a receptacle for use with the present invention showing, in phantom, a syringe guide in operative relation therewith and syringes in place therein;

FIG. 28 is a top plan view of an alternate embodiment of a receptacle for use with the present invention similar to FIG. 27 with alternate length syringes in place therein;

FIG. 29 is a top plan view of an alternate receptacle for use with the present invention similar to FIG. 27 with syringes shown in phantom in place therein; and,

FIG. 30 is a top plan view of an alternate receptacle for use with the present invention showing alternate syringes in phantom in place therein.

Referring now specifically to the drawing, and first to FIGS. 1 and 2, in accordance with an illustrative embodiment demonstrating objects and features of the present invention, there is shown a receptacle-advancing and supplying mechanism or apparatus, generally designated by the reference numeral 10, which includes four receptacle channels 12 which are generally L-shaped and are mounted to be generally upstanding with respect to the apparatus 10.

Two of the channels 12 are located toward the front of the apparatus 10 (the right in FIGS. 1 and 2), being mounted by conventional means to be generally stationary with respect to the apparatus. Two of the channels 12 are located toward the rear of the apparatus 10 (the left in FIGS. 1 and 2). The two rear channels 12 are movable between a first position as shown in full lines in FIGS. 1 and 2, and a second, extended position shown in phantom in FIGS. 1 and 2 for a purpose to be described hereinafter. The channels 12 are arranged with the inside corner of the L facing diagonally in-

60

65

wardly so that the four channels 12 form the outline of the corners of a rectangle.

The two rear channels 12, which are movable as noted above to a second or extended position, are movable to the extended position while maintaining the same basic rectangular orientation of the four channels. Compare the full line representations of the rear channels 12 in FIGS. 1 and 2 with the phantom line representations therein.

The direction of feed for receptacles is noted by the directional arrows A in FIGS. 1 and 2. The longitudinal spacing along the direction of feed of the front channels 12 with respect to the rear channels 12 is such that the longitudinal dimension of a receptacle R, shown in phantom in FIGS. 1 and 2, is relatively confined in lateral movement. However, a receptacle R within the channels 12 is capable of relatively unconstrained vertical movement between the four channels within the rectangular area defined thereby.

In a like manner, the alternate position shown in phantom in the drawing for the rear channel members 12 is designed to retain a stacked array of receptacles R_L within the rectangular space defined by the two front and two rear channels 12 and likewise permit virtually unrestrained vertical movement of the stacked array of large receptacles for a purpose to be described hereinafter.

As may be noted by reference to FIGS. 2, 7, 8, 27 and 29, the receptacles R (or the receptacles R_L which are virtually identical thereto with the exception of being of greater longitudinal extent) include a central storage or container area which occupies most of the area of the receptacle. The receptacles R include inwardly sloping side walls R_S (see FIG. 10) which terminate at the upper end thereof in a flange R_F which extends around the entire periphery of the receptacle R. At the lower end of the receptacle R, it terminates in a bottom wall R_B.

The bottom wall R_B is constructed and arranged so that it rests upon the flange R_F of the next lower receptacle R for a purpose to be described hereinafter. The containers R may be made of lightweight plastic or aluminum or the like in order that parts thereof may be separated from other parts thereof for use in removal of all or of part of the contents thereof.

As may be best seen by reference to FIGS. 9, 10, and 11, the channels 12 are attached to support members 14 by any convenient means, such as by welding or the like, at their lower ends which may form part of an extension of the channels 12 or may be separate supporting members. The supporting members 14 are, in turn, affixed to a base 16 and the channels 12 are located to be spaced a distance above the base 16 and also above a support or transport bed 18, specifically the upper surface thereof, an amount at least equal to the height of one of the receptacles R for a purpose to be described more fully hereinafter.

The height of the space above the top surface of the support bed 18 may be made adjustable, if desired, if the apparatus of the present invention is to be adaptable for use with different sized receptacles.

Mounted on the base 16 on either side of the channels 12 and spaced outwardly therefrom (to the left and right thereof as viewed in FIGS. 9 through 11) are support blocks 20. The support blocks 20 extend above the base 16 a distance at least equal to the height of three receptacles R and extend longitudinally along the direction of advance A, toward the front of the machine.

Affixed to the top of each of the support blocks 20 is a receptacle contact means 22 which includes a contact member mounting plate 24 mounted to the support blocks 20 by bolts 26 or other convenient mounting means. The receptacle contact means 22 include hingedly fixed thereto by means of a hinge pin 28, a receptacle contact member 30. The receptacle contact member 30 is constructed and arranged to pivot into and out of contact with a receptacle in a manner to be described more fully hereinafter.

A spring mounting member 32 is located on the top of the mounting plate 24 and is affixed to the support block 20. The mounting member 32 includes a mounting nub for fixing one end of a compression spring 34 thereto. The other end of the compression spring 34 is fixed to a mounting nub on the receptacle contact member 30 for downwardly biasing the receptacle contact member. When the receptacle member is free to do so, it moves to a downward position shown in full lines in FIG. 10 (and in phantom in FIG. 11) and strikes an adjustable contact stop 36 which is fixed to the base 16. The adjustable stop 36 is adjustable by virtue of being threaded and located within a threaded hole in the base 16.

It should be noted that substantially identical but reversed apparatus exists on laterally opposite sides of the receptacle channels 12 as seen in FIGS. 9, 10 and 11.

Actuator or operating rods or members 38 extend through openings in the base 16 and a nylon or plastic rounded tip 40 is affixed to the upper end thereof for contact with the underside of the receptacle contact member 30 for a purpose to be described more fully hereinafter.

The lower ends of the actuator rods 38 are removably fixed to an actuator rod activator bar 42 which, as may be seen in FIGS. 10 and 12, is connected to additional apparatus for driving movement thereof in a manner to be described more fully hereinafter.

As may best be seen by reference to FIGS. 1, 2, 12, 13 and 14 a receptacle advancing arm 44 is generally rectangular and is mounted to the apparatus 10 with the lower surface thereof in proximity to the upper surface of the support bed 18 for use in advancing a receptacle R which has been deposited with the bottom surface R_B thereof in contact with the upper surface of the support bed along the support bed in a manner to be described more fully hereinafter.

The advancing arm 44 includes an overhanging lip 46 at its operating end at the right in FIGS. 1, 2, 12, 13, and 14 for engagement with the flange R_F of a receptacle R when used to advance the receptacle along the support bed 18 in a manner to be described more fully hereinafter.

The left or attachment of the advancing arm 44 is fixed to an advancing arm support 47 (see FIGS. 1, 2, and 12) which is connected, through connecting link 48, to an operating arm 50. The operating arm 50 is suitably journaled at its lower end to the base frame member 52 of the device and is pinned at pin 54 to the connecting link 48. (See FIGS. 3, 4 and 6). The operating arm 50 is biased toward an upstanding frame member 56 by a spring 58.

The operating arm 50 includes a cam follower 60 which bears against an advancing arm cam 62 which rotates about an operating shaft 64 powered by a standard power source which is not shown.

By virtue of the interconnection of the operating arm 50 through the connecting link 48 and the advancing arm support 47 with the advancing arm 44, the rotation of the cam 62 and the cam follower 60, the advancing arm 44 periodically reciprocates along the support bed 18 in a manner and for a purpose to be described more fully hereinafter.

Spaced to the right along the direction of advance or feed A, and positioned above the support bed 18, is a filling station 66 (see FIGS. 1 and 2), which supplies items to be contained within the receptacles which are advanced along the support bed and supported thereby.

The filling station 66 can be of a type to supply any one of a number of different items to be housed or contained in the receptacles R. In the preferred embodiment illustrated, the filling station 66 is shown as supplying syringes S from a grooved drum D which is supplied with the syringes from a hopper H located thereabove and only fragmentarily shown in FIGS. 2 and 12 but completely shown in FIG. 3 and in enlarged detail in FIGS. 15, 16 and 18.

The grooved drum D is periodically rotated a given amount by interconnection with a power source not shown, through ratchet wheel W which is fixed to a shaft W_s to which the grooved drum D is fixed.

A brake device B which may be of any standard manufacture is fixed to the hopper H and ensures that the shaft W_s to which the grooved drum D is affixed does not rotate past the intended stopping point under the action of the impetus supplied thereto by the ratchet wheel W by applying a constant braking force to the shaft W_s. The brake B is shown in FIG. 19.

The syringes S are designed to be released through a syringe guide SG fixed to the front wall 68 of the machine and are deposited into a receptacle R which has been advanced by the advancing mechanism to be described more fully hereinafter until it abuts an adjustable stop 70 and is positioned under the grooved drum D of the filling station 66. Larger syringes are released through a larger syringe guide SG' (see FIGS. 25, 29 and 30) into a larger receptacle R_L.

The adjustable stop 70 includes a slot 72 therein by which it is affixed to the front wall 68 of the machine and may be adjustably located with respect to the grooved drum D by use of the bolt and wing nut arrangement 74 which passes through the slot 72 and through an opening in the machine wall.

Adjustment of the stop 70 is necessitated by the fact that the machine of which the device 10 is a part is adjustable for supply and delivery of either large or small receptacles R, R_L respectively. Naturally, if the larger receptacles R_L are to be supplied, the stop 70 would be moved to the right in FIGS. 1 and 2 in order that the receptacle R_L would be correctly positioned under the grooved drum D of the filling station 66 when it was advanced by the advancing mechanism in order that delivery of the syringes S could be effected.

As will be discussed more fully hereinafter, the receptacles R or R_L, once they are delivered to and supported by the support bed 18, are advanced therewith by operation of the advancing arm 44 by abutting a just-released receptacle delivered by the delivery apparatus and pushed from under the four channels 12. The advancing arm 44 then retracts or moves to the left as seen in FIGS. 1, 2 and 12, another receptacle R is delivered to the support bed 18 and is, in turn, advanced along the support bed. This last-named receptacle R in

turn, advances the previously delivered and advanced receptacle ahead of it along the support bed.

This advancing of delivered receptacles continues until a receptacle abuts the adjustable stop 70 and the filling station 66 operates to deliver a predetermined number of syringes S thereto. As noted above, the receptacles R which are advanced along the support bed 18 and supported thereby are made of generally light plastic or other material. Consequently, the receptacles R have a natural tendency to ride up on one another which would cause buckling of two adjacent receptacles thereby interfering with normal operation of and jamming the machine, specifically the apparatus 10.

In order to prevent this overriding and buckling, receptacle guides 76 are affixed to, partially override and are spaced above the support bed 18 on either side thereof. The guides 76 are sized to extend over part of the side edges of the receptacles R to maintain the bottom surface R_B of the receptacles R in contact with the support bed 18 as they are being advanced therewith. The guides 76 thereby prevent buckling of adjacent receptacles R as they are advanced along the support bed 18 toward the filling station 66.

The guides 76 are located adjacent the front channels 12 in the direction of advance A along the support bed 18. If the apparatus 10 is to be set up for advancing a regular length receptacle R, it will be necessary for the advancing arm 44 to extend beyond the front channels 12 during the advancing stroke and extend a given distance between the guides 76.

In order to permit entrance of the advancing arm 44 between the guides 76, a reduction in the transverse dimension of the top of the advancing arm 44 is necessary. The required transverse reduction is accomplished by chamfering the top outside corners 78 of the arm 44 (see FIG. 13).

When a longer tray R_L is to be advanced, the advancing arm 44 is removed and a somewhat shorter arm 80, which includes an overhanging lip 82 at the operating end to the right thereof, is attached to the advancing arm support 47. In view of the extra length of the receptacle R_L, the advancing arm 80 is shorter than the advancing arm 44 and it is not necessary for the operating end at the right of the advancing arm 80 to extend between the guides 76. Consequently, there is no necessity for chamfering the top outside edges of the operating arm 80.

As the receptacle R is advanced along the support bed 18 by being pushed by an abutting receptacle R located therewith which is being advanced by an advancing arm 44 or 80, it leaves the bed 18 and the lower surface thereof is supported on ledges 84, 84', on either side of top (left) and bottom (right) receptacle support members 86, 86' when it abuts the adjustable stop 70 and is located under the grooved drum D.

The top or left receptacle support member 86 is, in turn, supported on a shaft 88 (see FIG. 1) which is journaled at the forward or right end in the wall 68 and attached at the rear or left end to a pinion gear 90. The pinion 90 is in mesh with a rack 92.

The bottom receptacle support member 86', as viewed in FIG. 1, includes a receptacle support ledge 84', is attached to a shaft 88' which is likewise journaled in the wall 68 on the forward end and affixed to the pinion 90' at its left or rear end which is in mesh with a rack 92' in much the same manner as is the receptacle support member 86.

The racks 92, 92' are reciprocated by attachment to an operating arm 94 (see FIGS. 4 and 12) in a conventional manner. By virtue of conventional cams and cam followers the operating arm 94 is caused to periodically reciprocate in timed relation to the operation of the device in a manner to be described hereinafter.

The receptacle support members 86, 86' are constructed so that the ledges 84, 84', which support a receptacle R, are rotated in the direction of the directional arrows O in FIG. 1 by the interconnection of the racks 92, 92' and the pinions 90, 90' to periodically remove support from underneath the receptacle R, thus permitting the filled receptacle containing syringes S to drop down onto a conveyor system C in the direction of the directional arrows V (see FIGS. 2 and 12). Once filling of the receptacle R has been completed it is removed for further operation or packaging.

After the filled receptacle R is removed by the removal conveyor C, the racks 92, 92' are reciprocated to rotate the ledges 84, 84' of the receptacle support members 86, 86' back to a horizontal position. In the horizontal position, the ledges 84, 84' are arranged to receive the next advancing receptacle R, in a manner to be described more fully hereinafter, for receipt of additional syringes S therein.

The operation of the subject device will now be discussed with reference to receptacles R though it is to be understood that virtually the entire operation of the device is substantially identically the same when receptacles R_L of a larger size are to be dispensed and supplied.

The channels 12 are arranged to enclose or bound a generally rectangular area between the inside corners thereof substantially equal to the outer boundary of a receptacle R by affixing the channels to the device 10. A supply of receptacles R are aligned and stacked one upon the other between the bounds of the four channels 12 with their bottom walls R_B lowermost with the stacked array extending upwardly within the rectangular bounds of the channels 12. The receptacles are sized, as noted above, to be substantially freely movable within the bounds of the channels in a vertical direction and generally rest with the bottom wall R_B of all but the lowermost receptacle on the flange R_F of the next lower receptacle.

In the starting position of operation of the device 10, the contact rods 38 are in their uppermost position by virtue of the operating arm 96, which is pivoted at its rear or left end as seen in FIG. 12 to the upright frame member 56, being raised to its highest position. This position of the operating arm 96 occurs through contact of the cam follower 98 with a high point on the operating arm cam 100 and by virtue of the connection between the actuator bar 42 and the operating arm 96 through the connecting mechanism 102 as best shown in FIG. 12.

With the aforementioned upper position of the contact rods 38, the plastic or nylon inserts 40 on the ends thereof bear against and raise the receptacle contact members 30 to their upper position as shown in FIG. 11 by pivoting them about the pins 28 thereby compressing the springs 34 between the receptacle contact members and the members 32.

With the receptacle contact members 30 in their uppermost position as shown in full lines in FIG. 11, the receptacles R, placed within the boundaries of the four upstanding channels 12, come to rest with either the bottom wall of the containers R_B or the flange R_F

thereof contacting the upwardly pivoted contact members 30.

The ends of the contact members 30 are spaced apart a distance which, when they are in their upper position just described, must be at least less than the transverse distance of the flanges R_F and which, in the preferred embodiment, is approximately equal to the transverse distance between the side walls R_S of the receptacles R for a purpose to be described more fully hereinafter.

As may be seen by reference to FIGS. 1, 2 and 9, the location of the receptacle contact section of the receptacle contact member 30 (which is the part thereof that extends transversely outwardly from the main, longitudinally extending part thereof) is located to protrude between two of the front and rear channels 12 to contact the receptacle R.

With the receptacle contact section of the receptacle contact member 30 in the position illustrated in full lines in FIG. 11, the lowermost receptacle R and the additional receptacles (the next to lowermost, the next to next to lowermost, etc.) are in stacked vertically extending array thereabove as shown in FIG. 11. When the apparatus is in the position shown in FIG. 11, the bottom surface R_B of the lowermost receptacle of the stack is raised so as to be above the bottom of the channel 12 and, as may be noted in FIG. 11, a previously delivered receptacle is resting on the support bed 18. At that condition, the operating arm 50 is actuated by the interaction between the cam 62 and the cam follower 60 to operate the advancing arm 44 and move it in the direction of the directional arrows A.

As the actuating arm 50 moves the advancing arm 44, through the linkage 47, 48, in the forward direction, the lip 46 at the forward or operating end of the arm 44 overlies the flange R_F at the rear of the just-delivered receptacle R (which has been delivered by a process to be described in detail hereinafter) and urges the delivered receptacle toward the front of the machine and alignment with the filling station 66.

The cam 62 and the cam follower 60, in conjunction with the return spring 58 fixed to the arm 50 and the upstanding frame member 56, cooperate to move the advancing arm 44 rearwardly (as shown by the dashed arrow A' as seen in FIG. 9) after the operating arm 44 has urged the receptacle R along the support bed 18. The forward end of the receptacle is located a distance along the support bed 18 which is approximately one half of the distance between the area directly under the four channels 12 and the delivery station 66.

In being transported along the support bed 18, support of the bottom surface R_B of the receptacle R by the support bed 18 and contact therewith is assured by the fact that the side flanges of the receptacle are located beneath the guides 76 which partially overlie the support bed 18.

The delivered (previously lowermost) receptacle, as noted above, stops its forward movement approximately midway between the delivery apparatus or station and the filling station 66. The just-mentioned (previously lowermost) receptacle is advanced to the position under the filling station 66 by the next-delivered receptacle from the stacked array of receptacles in a manner to be described.

By positioning the cams, 62, 100, and others shown for example, in FIGS. 3, 6 and 8, correctly about the shaft 64, the cam followers in contact therewith, in proper timed relation to one another, in a conventional manner, operate the receptacle advancing mechanism

just described; the receptacle delivery mechanism about to be described; the article delivery mechanism wherein the syringes S are supplied to a receptacle once it reaches the correct position against the stop 70 under the grooved drum D; and, the receptacle support members 86, 86' to deliver the filled receptacle to the conveyor means C for removal from the machine area.

As noted above, when a receptacle R is advanced, the advancing arm 44 is utilized which includes the chamfers 78 to permit passage thereunder beneath the guides 76. If a longer receptacle R_L is to be advanced, the shorter advancing arm 80 is utilized which does not contain the chamfers as the operating end of the advancing arm 80 does not need to travel under the guides 76 to remove the just-delivered receptacle R_L out from under the delivery mechanism or apparatus.

Once the just-delivered (formerly lowermost) receptacle has been removed from under the channels 12 forming the bounds of the stacked array of receptacles, the operating rods 38 are moved downwardly through appropriately timed rotation of the shaft 64, the cam 100, the cam follower 98, the operating arm 96, the connecting mechanism 102, and the actuator bar 42.

The biasing springs 34 cause the receptacle contact members 30 to move downwardly, pivoting about the pin 28, thereby permitting the now lowermost (previously next to lowermost) of the stack of receptacles R contacted by the contact section of the contact member 30 to move downwardly, thereby permitting the entire stack of receptacles to move downwardly as well.

As may be most clearly seen by reference to FIGS. 10 and 11, the length and attachment of the receptacle contact members 30 are such that when the operating members 38 move to their lowermost position and the receptacle contact members 30 bear against the stops 36, the lowermost of the stacked receptacles and the stacked array thereabove has been considerably lowered as well. Owing to the arcuate path of the receptacle contact section, by the time the end of the member 30 abuts the top of the stop 36, it has pivoted out of contact with the lowermost receptacle which is lowered by virtue of the weight of the receptacles stacked thereabove until it contacts the transport bed 18 and is thus out of reach of the receptacle contact members 30.

Judicious shaping and attachment of the cam 100, the cam follower 98, and the other associated apparatus, subsequently causes the actuating rods 38 to move upwardly and bear against and raise the receptacle contact members 30 which pivot past the lowermost receptacle which is resting with its bottom surface R_B being supported on the bed 18. The receptacle contact members 30 now contact either the side wall R_S or the side flange R_F of the next to lowermost receptacle, or both the side wall and flange of the receptacle, and raise the next to lowermost receptacle and the stacked array of receptacles located thereabove out of contact with the lowermost, just-delivered receptacle. At this juncture, the cam 62 and associated mechanism can be arranged to actuate the advancing arm 44 to advance the just-delivered receptacle along the support bed 18 in the direction of the directional arrow A.

When the newly advanced receptacle contacts the previously advanced receptacle, the existence of the side grooves 76 will prevent buckling of one receptacle with respect to another. In addition, the engagement of the lip 46 or 82 on the advancing arms 44 or 80 likewise prevents buckling of a receptacle being advanced with respect to the arm 44 or 80.

The previously delivered and previously advanced receptacle R will advance off of the support bed 18 to be supported by the flanges 84, 84' of the receptacle support members 86, 86'. Here again, judicious positioning of the flanges 84, 84' is accomplished by virtue of cams and cam followers acting through mechanisms which include the racks 92, 92' and pinions 90, 90' so that the flanges 84, 84' are located to be in their generally horizontal position.

10 The ratchet wheel W is actuated by still other cams and cam followers to supply either one or a plurality of syringes S to the last-mentioned receptacle which is being supported by the flanges 84, 84' under the grooved drum D within the filling station 66.

15 As noted above, once the syringes S are in place within the receptacle R, the receptacle-supporting members 86, 86' are rotated by the racks 92, 92' and pinions 90, 90' to move the ledges 84, 84' in the direction of the directional arrows O in FIG. 1 to thus permit the filled receptacle to drop onto the conveyor C or other removal device and thereby be removed from the machine for further processing or packaging.

20 In general, the timed sequence of the delivery and supply operations would require that the lowermost receptacle in the stacked array be delivered when the advancing arms 44 or 80 had returned to the position wherein the forward (rightmost) or operating end of either would be in a position where no part thereof was under the delivery area defined by the four channels

25 12. This arrangement ensures that when the receptacle R was advanced onto the flanges 84, 84' of the receptacle support members 86, 86', the flanges would be rotated to their horizontal location in order to support the receptacle to be received under the filling station 66.

30 35 Naturally, the cams and cam followers such as described may be replaced by other timing mechanisms which can be wholly or completely electric or electronic rather than mechanical.

35 40 The nylon or plastic inserts 40 on the ends of the actuating rods 38 greatly reduce friction and wear therebetween and the underside of the receptacle contact members 30, and are easily replaceable should they become worn. In addition, should adjustment be necessary to compensate for wear, the ends of the actuating rods 38 opposite the nylon or plastic inserts 40 are threaded within the actuating bar 42 and provision may be made for adjusting the position of the rods 38 with respect to the bar 42 to compensate for wear of the inserts 40.

45 50 55 60 65 50 If it is desired to utilize receptacles without flanges, the receptacle contact members 30 may be made adjustable in the lateral direction by being mounted with the bolts 26 through slots (not shown) in the mounting plate 24 to permit the required adjustment. This adjustment would make it possible to have the receptacle contact members 30 pivot into sufficient engagement with the side walls of non-flanged receptacles to permit sufficient contact for lifting the contacted receptacle and those in stacked array thereabove. It has been found, however, that the flanged receptacles shown are preferred even though the side walls R_S are contacted with sufficient force to slightly flex the side walls when the lowermost receptacle is being supported with the flange acting as an additional support for contact of the receptacle by the receptacle contact members 30.

65 What has been described is a device for reliably and repeatably singly dispensing one of a plurality of stacked lightweight receptacles and advancing the

same toward a filling station without permitting buckling of adjacent receptacles and providing relatively simple mechanism for the accomplishment of the stated objectives of the device.

As will be readily apparent to those skilled in the art, the invention may be used in other specific forms or for other purposes without departing from its spirit or essential characteristics. The present embodiment is, therefore, to be considered as illustrative and not restrictive, the scope of the invention being indicated by the claims rather than by the foregoing description, and all changes which come within the meaning and range of equivalents of the claims are therefore intended to be embraced therein.

What is claimed is:

1. In a device for dispensing and delivering a receptacle to a station to receive an item therein; the improvement comprising upstanding channel members for maintaining receptacles in stacked array; a support bed spaced below the channel members and extending to the item receiving station; receptacle contact members hingedly mounted on opposite sides of the channel members to contact the lowermost receptacle and initially support the receptacles in stacked array; actuator rods reciprocally mounted below the receptacle contact members; springs biasing the receptacle contact members into contact with the actuator rods; means to reciprocate the actuator rods and actuate the receptacle contact members to three positions, the first position to engage the lowermost receptacle and support said lowermost receptacle out of contact with the support bed, the second position to lower said lowermost receptacle and stacked array and position the lowermost receptacle on the support bed, and the third position to engage the next to lowermost receptacle and raise the stacked array from the lowermost receptacle on the support bed; means to advance the lowermost receptacle on the support bed toward the station; and means for guiding and maintaining said advancing receptacle on the support bed.

2. In a device for dispensing and delivering a receptacle to a station to receive an item therein as claimed in claim 1, stop means adjustably mounted below the re-

ceptacle contact members to limit the lowermost position of said receptacle contact members out of contact with the receptacles in stacked array.

3. A device for dispensing and delivering a receptacle to a station to receive an item therein as claimed in claim 1, wherein the means to reciprocate actuator rods comprise an activator bar carrying said actuator rods, and a first cam operatively connected to and reciprocating said activator bar.

4. A device for dispensing and delivering a receptacle to a station to receive an item therein as claimed in claim 1, wherein the means to advance the lowermost receptacle on the support bed toward the station comprise an advancing arm reciprocally mounted above the support bed, and a second cam operatively connected to and reciprocating said advancing arm toward the lowermost receptacle on the support bed subsequent to the second position of the contact members.

5. A device for dispensing and delivering a receptacle to a station to receive an item therein as claimed in claim 4, wherein the forward end of the advancing arm is arranged with a lip to maintain contact with the lowermost receptacle on the support bed and chamfers in the upper side edges of the forward portion to permit entrance of the advancing arm below the guiding means.

6. A device for dispensing and delivering a receptacle to a station to receive an item therein as claimed in claim 1, wherein the means for guiding and maintaining the advancing receptacle on the support bed comprises guides spaced above opposite side portions of said support bed.

7. A device for dispensing and delivering a receptacle to a station to receive an item therein as claimed in claim 1, wherein the support bed below the station comprise spaced members rotatably mounted and arranged with ledges to support the receptacle at the station, and means to rotate said spaced members and position the ledges out of supporting contact with said receptacle to discharge the filled receptacle from the support bed by gravity.
